UNITED STATES PATENT OFFICE.

ELISHA S. WINN, OF CULLODEN, GEORGIA.

MOP.

1,148,561.

Specification of Letters Patent.

Patented Aug. 3, 1915.

Application filed January 28, 1915. Serial No. 4,882.

To all whom it may concern:

Be it known that I, ELISHA S. WINN, a citizen of the United States of America, and resident of Culloden, in the county of Monroe and State of Georgia, have invented certain new and useful Improvements in Mops, of which the following is a specification.

This invention relates to mops and particularly to means for clamping a scrubbing 10 or mopping material so that it may be manipulated over a surface to be oiled, washed or dusted, the said invention providing means for clamping the said material, yet affording means whereby the said scrubbing 15 material may be removed and replaced when it becomes worn or that other material may be substituted for that previously used.

An object of this invention is to provide 20 a clamping device comprising a plurality of metallic parts which will withstand hard wear without the elements thereof becoming disassociated or loosened and the said invention further contemplates the provision of novel means in the nature of clamping plates corrugated to augment the clamping 25 action of the said plates on the fabric, fiber or material constituting the scrubbing element.

A further object of this invention is to 30 provide a device between the handle of the mop and the scrubbing element in which the parts constituting the connection and coacting for that purpose may be interlocked in a manner to withstand unusual pressure on 35 the handle during the manipulation of the mop.

With the foregoing and other objects in view, the invention consists in the details of construction, and in the arrangement and 40 combination of parts to be hereinafter more fully set forth and claimed.

In describing the invention in detail, reference will be had to the accompanying drawings forming part of this specification 45 wherein like characters denote corresponding parts in the several views, and in which—

Figure 1 illustrates a vertical sectional view of a fragment of a mop handle with the clamping members for the scrubbing element associated therewith; Fig. 2 illustrates a sectional view on a line corresponding with the line 2—2 of Fig. 1; Fig. 3 illustrates a perspective view of one of the clamping plates; Fig. 4 illustrates a perspective view of the clamping member; Fig. 5 illustrates a sectional view on a line corre-

sponding with the line 5—5 of Fig. 1 which shows one form of the core; Fig. 6 illustrates a transverse sectional view similar to that shown in Fig. 1, but showing a core of another form; Fig. 7 illustrates a perspective view of clamping plates and a clamping member associated with strands of material constituting the mopping element, which mopping element is here shown as a modification of the fabric which constitutes the scrubbing element shown in Fig. 1; Fig. 8 illustrates a perspective view of a fragment of a clamping member slightly modified; Fig. 9 illustrates a sectional view of a fragment of a mop handle showing a means for retaining the arms in place, the said means being a part of the handle; and Fig. 10 illustrates a sectional view on a line corresponding with the line 10—10 of Fig. 9.

In these drawings 7 denotes a mop handle and said mop handle has applied thereto a sleeve 9, corrugated to form the threads 10 although the threads may be formed in any appropriate way, preferably intermediate the length of said sleeve. After the sleeve has been applied, it is secured to the mop handle by a fastener, such as 10^a. The purpose of the threads 10 is to engage arms 11 of the clamping member 12, it being seen from an inspection of Figs. 1, 2, 4 and 7 of the drawings that the ends 13 of the clamping members are bent or corrugated to engage the threads 10 of the sleeve 9.

In the form of the invention illustrated in Figs. 1 and 5, a core 7^a is inserted in the sleeve and said core has longitudinally disposed slots 8 forming seats for the arms of the clamping member, so that when the said arms are situated in the slots of the core, and the core and arms are inserted in the sleeve, springing action of the arms is prevented and the corrugations thereof cannot disengage from the threads of the sleeve by which the mopping or scrubbing element is connected to the handle. But for the presence of the core, there is liability of such disengagement under working conditions and therefore, the core acts as a guard to prevent accidental dislodgment of the ends 105 of the arms from the said threads.

Coacting with the clamping member 12 are the corrugated plates 14 and 15, which have apertures 16 and 17 respectively, the said apertures being in alinement and the 110 said apertures being designed for the reception of the arms of the clamping member.

As shown in Fig. 1 of the drawings, the arms of the clamping members extend through the apertures of the plates and project into the sleeve 9 and as the arm is 5 rotated, the plates are drawn together to clamp or retain the scrubbing elements 18 and 19 which are interposed between the said clamping plates. In addition to the plates 14 and 15 being corrugated, they 10 have side edge flanges 20 and 21 respectively, over which the scrubbing element is folded or bent so that the said scrubbing element may present comparatively broad surface to be forced into contact with the 15 floor or object being washed or treated by the mop.

In Fig. 7, the modification consists in the substitution of strands of material 22 constituting the mopping element for the fibrous 20 material 18 and 19 constituting the scrubbing element shown in Fig. 1 of the drawings, the substitution being illustrated to show the various uses or utilities of the invention and that it is susceptible of modifications 25 to suit particular requirements.

The form illustrated in Fig. 6, has an internal sleeve or core in place of the solid core, it being understood that the internal sleeve or core in this construction is to coact 30 with the arms and the threaded sleeve for retaining the clamping member in proper position. In this form, the internal core is designated by the reference character A while the outer sleeve B is similar to the 35 sleeve 9 which has been heretofore described, the arms C in this form corresponding to arms 11 in Fig. 4 engaging the threaded sleeve B as in the form first described. The core A has longitudinally disposed 40 grooves D formed preferably by stamping the metal of which the core is formed or the grooves may be otherwise produced to form seats for the arms of the clamping member. In applying the clamping member 45 to the sleeve of the handle, the arms of said clamping member are inserted in the grooves of the core and the said core, together with the arms, is rotated in the sleeve and as the corrugations of the said arm engage 50 the threads of the sleeve, the arms and core are drawn into the sleeve. It is to be understood, therefore, that the core may be of solid material, such as wood or metal, or it may be of tubular metal, as in the 55 forms here shown.

Fig. 8 illustrates a further modified construction in which the arm 11^a of the clamping member has a right angular extension 13^a adapted to engage the threads of a sleeve and in certain phases of use or manufacture of the invention, this form may be found preferable, the same depending upon the strength of the material used in forming or 60 making the clamping members.

From the foregoing description, it will

be seen that provision has been made for utilizing the core for retaining the arms of the clamp, the said core being rotatable with the said arms. In the embodiment of the invention shown in Figs. 9 and 10, I provide a handle 23 and reduce the lower end to form an extension 24, which might be said to constitute a core, and as in the other form, I have a sleeve 25 which is threaded to engage the arms 26, there being a space between the sleeve and the extension equal or approximately equal to the thickness of the arms so that the arms may be screwed into the sleeve and enter the space between the sleeve and the extension. In this form of 75 the invention, the extension prevents the arms of the clamping member from springing out of engagement with the threads of the sleeve, but otherwise the clamping member may be associated with clamping plates 80 and other devices, not shown, in this embodiment, as in the construction heretofore described.

I claim—

1. In a mop, a handle, a threaded sleeve 90 attached to said handle, clamping members having arms adapted to engage the threads of the sleeve, a core adapted to fit in the sleeve and to hold the arms in engagement with the threads of the sleeve, plates having 95 coinciding apertures, a mop interposed between the plates and clamped therein by the action of the clamping member engaging one of the plates and the end of the sleeve engaging the other of said clamping plates, 100 whereby said plates are forced toward each other.
2. In a mop, an element having grooves 105 therein, a clamping member having arms lying in the said grooves, a sleeve to receive said arms and said element and coacting to interengage for holding the parts in assembled positions, clamping plates having coinciding apertures through which the arms 110 of the clamping member extend, a mopping element between the said plates, one of said plates being engaged by the sleeve whereby it is held against movement while the opposite plate is moved with relation to it.
3. In a mop, an element having grooves 115 therein, a clamping member having arms lying in the grooves, said arms having thread engaging portions thereon, a sleeve adapted to receive the said element and the arms of the clamping member, said sleeve having 120 threads coacting with the thread engaging portions of the arms, a plate engaged by the end of the sleeve, a plate spaced apart from the first mentioned plate, said plates having coinciding apertures through which the arms of the clamping member extend, and a mopping element interposed between 125 the said plates.
4. In a mop, a handle, a threaded sleeve 130 attached to the handle and projecting from

the end thereof, a clamping member having arms for engaging the threads of the sleeve, a core having slots to receive the arms of the clamps for limiting the inward movement of the arms, and mop holding members carried by the clamping member.

5. In a scrubbing device, a handle, a sleeve secured to the handle and projecting from an end thereof, said sleeve being threaded, 10 a clamping member having arms provided

with means for engaging the threads of the sleeve and a core within the sleeve spaced therefrom and operative to hold the arms in engagement with the threads of the sleeve.

In testimony whereof, I affix my signature 15 in the presence of two witnesses.
